ATTORNEY

UNITED STATES PATENT OFFICE.

FRANK W. SMITH, OF WESTFIELD, NEW JERSEY.

REGULATOR FOR ELECTRIC FURNACES.

1,282,478.

Specification of Letters Patent. Patented Oct. 22, 1918.

Application filed January 5, 1918. Serial No. 210,497.

To all whom it may concern:

Be it known that I, FRANK W. SMITH, a citizen of the United States, residing at Westfield, in the county of Union and State 5 of New Jersey, have invented a certain new and useful Regulator for Electric Furnaces, of which the following is a specification.

My present invention relates to a regulator for electric furnaces, particularly arc 10 furnaces, of the type in which the position of the electrodes or movable elements of the furnace is automatically adjusted in response to variations of current in the electrode circuits either above or below a predetermined normal value, the object being to 15 provide a system of regulation which is simple and efficient and which will move the electrodes to the extent, and only to the extent, required to restore the current to its 20 normal value.

To this end, the invention comprises, broadly stated, a fluid motor operatively connected with an electrode and adapted to move it to adjust the length of the arc and 25 means controlled by the electrical condition of the electrode circuit for controlling the operation of the motor. It also includes the novel features of construction, arrangement, and combination of parts hereinafter 30 described and particularly pointed out in the annexed claims.

The accompanying drawing, in its single figure, illustrates, more or less diagrammatically, a regulator embodying my invention 35 as applied to one of the electrodes of a well-known alternating current arc furnace, it being understood that a similar regulating device may be associated with each of the other furnace electrodes.

Referring to this drawing, the furnace 40 comprises a suitable receptacle 1 containing the usual conductive charge 2 and an electrode 3 (with others, not shown,) connected to the supply wire 4 of an alternating current supply system, the other electrodes being 45 in like manner connected to the supply wires 5 and 6. A fluid motor 7, which may be a compressed air or other commercial motor of any suitable construction, is operatively connected with the electrode by means, as here shown, of a pivoted lever 9 which at one end is suitably connected with the piston rod 8 of the motor and at its other end is connected to a link 10 attached, preferably

adjustably, to the upper end of and supporting the electrode. The motor is operated by motive fluid from a supply pipe 11, connected with a storage tank 12 or other source of supply, admitted either to the upper end of its cylinder through a pipe 13 or to its 60 lower end through a pipe 14 under the control of a valve 15, of any well-known type, which at the same time that it connects pipe 13 with the supply pipe will connect pipe 14 with an exhaust 16, preferably provided 65 with a valve as shown to regulate and adjust the size of the exhaust opening, and, reversely, will connect pipe 13 with the exhaust when pipe 14 is connected with the supply-pipe. This valve is actuated, through 70 a lever-arm 17 which is restored to and normally held by centering springs 18 and 19 in a position adapted to cut off the motor from both supply and exhaust, either manually, whenever found desirable, or automatically by means of one or the other of two 75 magnets 20 and 21. The circuits through the actuating coils of these magnets, adapted to be connected across the supply wires 4 and 6 and including wires 22, 23, 24 and 22, 80 25, 26, respectively, are in turn controlled by a relay which comprises a movable switch-contact 27 in electrical connection with circuit wire 22, two fixed contacts 28 and 29 connected respectively with circuit 85 wires 23 and 25, and operating magnet 30 whose coil is in closed circuit with a transformer coil 31 on the supply-wire 4, and, preferably, an adjustable spring 32 adapted to sustain the weight of the movable parts 90 of the relay and a dash-pot 33 also preferably adjustable. The position of each of the other electrodes is, or may be, regulated in the same way from a transformer coil like the coil 31 on the supply wire of the electrode. All the further details of construction of the several parts of the apparatus 95 will be fully understood by those skilled in the art.

The parts of the regulating device are so 100 adjusted that, when the current in the supply wire 4 is of predetermined normal value, the movable contact of the relay will be held in position intermediate the two fixed contacts thereby cutting both magnets 20 and 105 21 out of circuit, the valve of the motor will be held by the centering springs in position to close the two ends of the motor cylinder

both to the supply-pipe and to the exhaust, and the piston of the motor and consequently the electrode will remain stationary. Whenever, however, the current in the 5 supply wire falls below such value, owing to a lengthening of the arc due to the wearing away of the electrode or to any other cause, the weakening of the magnet of the relay will permit its movable contact to 10 drop against the lower contact 25. This closes the actuating circuit of magnet 21, which, provided there is current on the supply wires 4 and 6, will immediately draw down the lever-arm and so move the valve 15 as to connect the lower end of the motor cylinder with the supply pipe and its upper end with the exhaust. The piston of the motor is accordingly moved upward, and the electrode is moved downward and 20 shortens the arc, at a rate determined, for example, by the adjustment of the valve in the exhaust. Or, reversely, if for any reason the current in the electrode circuit rises above normal, the electrode will be raised 25 and the arc lengthened since the magnet 20 will be energized by the action of the relay and will connect the upper side of the motor cylinder with the supply pipe. In either event, as soon as the length of the arc has 30 been so adjusted as to restore the electrode current to normal, the relay will open the circuit of the magnet 20 or 21, as the case may be, and the motor will be shut off and will instantly stop without overrunning.

35 The centering springs 18 and 19, it will be seen, also serve as a means for automatically shutting off the motor and stopping the movement of the electrode whenever there is a failure of voltage on the supply 40 wires, while the valve in the exhaust provides a convenient means for regulating the rate of travel of the motor piston either to speed it up, which may be found desirable when a short used-up electrode is to be replaced with a new one and under other operating conditions, or to slow it down.

45 It is, of course, to be understood that the invention is not limited to any feature or detail of the specific regulating device herein illustrated and described, except as set forth in the appended claims.

50 What I claim, as new, and desire to secure by Letters Patent, is—

1. In combination, an electric circuit, a 55 movable element therein, a fluid motor operatively connected with the movable element, electromagnetic means normally cut out of circuit for controlling the motor, and means responsive to changes in the electrical condition of the circuit for controlling said electromagnetic means.
2. In combination, an electric circuit, a 60 movable element therein, a fluid motor operatively connected with the movable element, two electromagnets adapted when en-

ergized to start the motor one in one direction and the other in the other direction, and means controlled by the electrical condition of the circuit for controlling the electromagnets.

3. In combination, an electric circuit, a 70 movable element therein, a fluid motor operatively connected with said movable element, two electromagnets normally out of circuit and adapted when energized to control the motor, and means responsive to variations in the electrical condition of the circuit for controlling the electromagnets.

4. In combination, an electric circuit, a 75 movable element therein, a fluid motor operatively connected with the movable element, and means responsive to variations in the electrical condition of the circuit for controlling the motor and adapted to automatically shut it off on failure of voltage 80 on the circuit.

5. In combination, an electrode, a supply 85 circuit therefor, means for moving the electrode to adjust the length of the arc formed thereby, and electromagnetic means normally cut out of circuit and controlled by the electrical condition of the electrode supply circuit for controlling the electrode moving means.

6. In combination, an electrode, a supply 90 circuit therefor, a fluid motor operatively connected with the electrode and adapted to move it to regulate the length of the arc formed thereby, means responsive to variations in the electrical conditions of the supply 95 circuit for controlling the motor, and means for regulating the speed of operation 100 of the motor.

7. In combination, an electric circuit, a 105 movable element therein, a fluid motor operatively connected with the movable element, and means responsive to variations in the electrical condition of the circuit for controlling the motor and adapted to automatically shut off the motor on failure of voltage 110 in the circuit.

8. A regulator for an electric furnace comprising an electrode, a circuit therefor, a 115 fluid motor adapted to change the position of the electrode, and means operated by current in the electrode circuit and controlled by variations thereof for controlling the motor.

9. A regulator for an electric furnace comprising an electrode, a circuit therefor, a 120 fluid motor adapted to change the position of the electrode, a valve controlling the motor, electromagnetic means for operating the valve, and means responsive to variations of current in the electrode circuit for controlling 125 said electromagnetic means.

10. A regulator for an electric furnace comprising an electrode, a circuit therefor, a 130 fluid motor adapted to change the position of the electrode, means for regulating the

speed of the motor, a valve for controlling the motor, and means responsive to variations in the electrical conditions of the electrode circuit for controlling the valve and 5 adapted to automatically move the valve to shut off the motor on failure of voltage on the electrode circuit.

11. A regulator for an alternating current furnace comprising an electrode, a circuit 10 supplying alternating current thereto, means for adjusting the position of the electrode to lengthen or shorten the arc, and means operated by current in the electrode supply circuit and responsive to variations in the elec-

trical condition thereof for controlling the 15 electrode adjusting means.

12. A regulator for an alternating current arc furnace comprising an electrode, a circuit supplying alternating current thereto, a motor adapted to move the electrode to 20 lengthen or shorten the arc, electromagnets energized by current in the supply circuit for controlling the motor, and means actuated by variations in the electrical condition of the supply circuit for controlling the elec- 25 tromagnets.
